TELEGRAPH SYSTEM

Application filed July 26, 1929. Serial No. 381,307.

This invention relates to telegraph systems and more particularly to receiving systems adopted for long telegraph lines.

The invention provides method and means whereby transmitted signals may be correctly received at the receiving station even although the speed of transmission is increased beyond that point at which each unit impulse, whose characteristics have undergone a change due to the electrical constants of the line, can effect operation of a line relay, even after amplification.

In the drawing comprising but a single sheet of one figure, is shown schematically a portion of the equipment which may be arranged at a telegraph station for effecting reception of signals in accordance with the present invention.

In the embodiment of the invention disclosed herein, a relay 1 is provided as a part of the receiving equipment, which relay, under the control of a distributor, is normally in a vibrating condition, regardless of whether any signals are being transmitted to such receiving equipment or not. This distributor rotates synchronously with a distributor at the station from which signals may be sent.

The two polar line relays 2 and 3, whose windings 4 and 5 respectively are connected in series with the output of an amplifier adapted to repeat the impulses received over the line, or submarine cable 40, are provided also with the respective windings 6 and 7. By reason of a weak current normally flowing through the windings 6 and 7 from the battery 8, armatures 9 and 10 are held against their respective contacts 11 and 12, when the current flowing through windings 4 and 5 is insufficient to cause them to move towards their opposite contacts. Contact 11 being permanently connected to armature 13 of relay 1, and armature 10 being permanently connected to conductor 14 which leads to solid ring 15 of the distributor, it will be seen that, so long as windings 4 and 5 remain deenergized, positive or negative potential can be applied to ring 15 through contacts 16 and 17 respectively of relay 1 depending upon the position of armature 13.

The continuous vibration of the armature 13 is effected in the following manner: The distributor is provided with a solid ring 18 to which is connected the grounded condenser 19, and with segmented 20 consisting of a series of groups of segments 22, 25, 27, 28. The brush 21 is adapted to pass over four successive segments during the time of transmission of each single unit impulse. Segments 22 are connected by a common conductor 26 through resistance 24 to ground; segments 25 are connected by a common conductor 23 to conductor 14; segments 27 have no external connection and segments 28 are connected by common conductor 29 to the winding of relay 1 through a resistance to ground. Now as brush 21 connects a segment 25 to ring 18, positive potential from battery 30 will be impressed on condenser 19, thus charging it. When the brush now reaches the next segment 28, the condenser is discharged through the winding of relay 1, and the armature 13 will pass from contact 16 to contact 17. In this position negative potential will now be placed on conductor 14. When the brush 21 reaches the next segment 22 any residual charge left in the condenser will be drawn off through resistance 24 to ground. The brush then reaches the next segment 25, condenser 19 is negatively charged and this charge, when the brush reaches the next segment 28, energizes relay 1 and armature 13 moves to the left and again contacts with contact 16. This cycle of operations will continue, thus keeping armature 13 in constant vibration so long as no impulses are being received.

Since the speed of transmission is so great that single unit impulses are too weak to be properly amplified at the receiving station, relays 2 and 3 will not respond to single unit impulses. That is to say, if an incoming signal is made up of the following combination of single unit impulses, positive, negative, positive and negative, these impulses would be supplied by the normal operation of relay 1 through conductor 14 to ring 15 and thence by means of brush 31 through segments 32 successively which are permanently connect-

ed to receiving printer magnets or storing relays.

Should, however, a signal be made up of positive, positive, negative and positive impulses, then, although relay 2 has not operated by reason of the first positive impulse, which will be filled in by relay 1, it will become operated due to the continued application of positive current. Its operation will cause its armature 9 to move to the right, and positive potential is thus maintained on ring 15 from battery 30 over contact 33. The polarity of relay 3 is such that its armature 10 does not move from contact 12 on positive impulses.

During the first positive impulse when brush 21 connected segment 25 with ring 20, condenser 19 became charged, just as though no signals in fact were being received. The condenser then discharged over segment 28 through the winding of relay 1 and armature 13 moved to the right and engaged contact 17. But inasmuch as armature 9 at this time had already moved from contact 11, negative potential from battery 8 is not communicated at this time to conductor 14.

During the second positive impulse, condenser 19 is again charged, but upon the subsequent discharge the armature 13 of relay 1 remains against contact 17 as the discharge is of the same polarity as that which caused the next preceding movement of the armature.

Now toward the end of the second impulse, as a change is being made from positive to negative signals, there will be a falling off in current strength, and a point will be reached where the current through windings 6 and 7 of relays 2 and 3 respectively is stronger than that through the line windings. Under such a condition, armature 9 will move to the left and re-engage with contact 11. Negative potential is at once supplied to conductor 14 over the following path, battery 8, contact 17, armature 13 contact 11, armature 9, contact 12, and armature 10. Thus the connection of negative potential to the ring 15 precedes the actual arrival of the negative impulse from the transmitting station, or takes the place of such impulse if it is not received or is not sufficiently well defined to effect the operation of one of the two line relays.

Each character or symbol consists of a series of positive, negative, or positive and negative impulses in combination. A single unit impulse is a current impulse of either positive or negative polarity impressed upon the circuit for a predetermined unit of time. A double, triple, (etc.) unit impulse is a succession of impulses of like polarity impressed upon the circuit for two or three (or more) time units.

Claims:

1. In a telegraph system, means responsive

to line signal impulses, a condenser, a distributor, a circuit closed under control of said distributor for charging said condenser, and a relay, a discharge circuit for said condenser including the winding of said relay closed under control of said distributor whereby said relay is energized wholly independent of whether or not line signal impulses are being transmitted through said system.

2. In a telegraph system and in combination a first relay means, a second relay means, and means including a condenser for maintaining the armature of said first relay means in a state of vibration when said second relay means is unoperated.

3. In telegraph receiver, selector means, a pair of normally biased polar relays, each of said relay having an armature adapted to respond to signal currents, a vibrating relay, and an operating circuit for said selector means controlled by said vibrating relay and extending through the armatures and contacts of said polar relays whereby the current in said operating circuit is reversed by the operation of either of said polar relays.

4. In a telegraph system a distributor, a local relay, a condenser, said local relay being arranged to vibrate under the influence of said distributor and condenser, and a line relay arranged to render said distributor and condenser ineffective to operate said vibrating relay.

5. In a telegraph receiver, a vibrating relay, a source of potential having opposite poles connected to the contacts of said relay, a pair of biased polar line relays, and a distributor ring, each of said line relays being operable to connect either positive or negative potential to said distributor ring and to arrest the action of said vibrating relay so as to retain the armature thereof on a contact of opposite polarity to that on said distributor ring.

6. In a telegraph system, the combination of a pair of receiving relays, and a vibrating relay having an operating circuit which is under the control of its own contacts and said receiving relays.

7. In a telegraph system, a pair of normally biased polar relays, and a vibrating relay, said vibrating relay having an operating circuit normally controlled by its own contacts and being arranged to operate in synchronism with impulses transmitted over said system and said polar relays being arranged to selectively control said vibrating relay.

8. In a telegraph system, a local circuit, line relay means, a polar relay, and a distributor having a plurality of segmented rings, the segments of one of said rings being arranged in a series of groups, a first group being arranged to charge a condenser;

and a second group being arranged to cause said condenser to discharge through the windings of said polar relay, said line relay means determining the polarity of said discharge.

9. In combination, three relays each having an armature having two operating positions and contacts to be engaged in each of such positions, a source of positive potential and a source of negative potential, each of said sources being connected to a contact of one of said relays and to a contact of one of the other two relays.

10. In a telegraph system a transmitting station a receiving station, a transmission line extending between said stations, means at said transmitting station for sending over said transmission line signals representing a message and composed of combinations of unit impulses of positive or negative polarity, auxiliary means at the receiving station adapted normally to supply alternately positive and negative impulses independently of the signals sent from the transmitting station to recording apparatus located thereat, and means operative upon the arrival of a unit impulse of the same polarity as that impulse immediately preceding to cut off said auxiliary means from said recording apparatus, and for a part at least of the duration of said unit impulse of the same polarity to control the operation of said recording apparatus.

11. In a telegraph system, the combination with the standard two relay receiving circuit of means effective when both receiving relays are in inoperative position to supply single unit impulses.

12. In a telegraph system, the combination with the standard two relay receiving circuit of means comprising a single wound vibrating relay effective when both receiving relays are in inoperative position to supply single unit impulses.

13. The combination with the standard two relay receiving circuit of means comprising a distributor effective when both receiving relays are in inoperative position to supply single unit impulses.

14. The combination with the standard two relay receiving circuit of means comprising a relay and a distributor effective when both receiving relays are in inoperative position to supply single unit impulses.
